UNITED STATES PATENT OFFICE.

CLARENCE LANTRIP, OF FOUKE, ARKANSAS.

BASKET-BALL GOAL.

Application filed March 22, 1923. Serial No. 626,727.

To all whom it may concern:

Be it known that CLARENCE LANTRIP, a citizen of the United States, residing at Fouke, in the county of Miller and State 5 of Arkansas, has invented certain new and useful Improvements in Basket-Ball Goals, of which the following is a specification.

My invention relates to improvements in basket ball goals and the main purpose 10 thereof is to substantially improve over similar devices with which I am now familiar.

A further purpose of my invention is the provision of such a basket ball goal which 15 is comparatively simple of construction, extremely inexpensive to manufacture and of such a nature as to be readily removed or applied to its supporting standard.

The nature and advantages of the invention will be better understood when the following detailed description is read in connection with the accompanying drawings, the invention residing in the construction, combination, and arrangement of parts as 25 claimed.

In the drawings forming part of this application, like numerals of reference indicate similar parts in the several views, and wherein:

30 Figure 1 is a side elevation of my improved goal applied to the usual goal supporting structure;

Figure 2 is a front elevational view thereof;

35 Figure 3 is a perspective of one of the supporting arms; and

Figure 4 is a top plan view of the goal.

Referring to the drawings in detail, 5 designates the usual supporting standard and 6 the board, it being understood that these elements do not comprise my invention as the same are found in practically all basket ball courts and are shown for permitting my improved goal to be more adequately disclosed.

45 My invention per se embodies a basket

carrying member designated in general by the numeral 7. This supporting member is formed from a single length of metal, the same being bent to provide a relatively 50 large wing 8, a web 9 and bracket members 10, the bracket members being secured as at 11 to the said board 6. The usual basket 12 of netting is secured in a well known manner to this ring 8 and does not comprise 55 any portion of my invention.

Between the opposite sides of the ring 8 and at a point adjacent the lower end of the board 6 are ring supporting arms 13, the lower ends thereof being bent at an angle 14 for face to face contact with the said board 6 and adapted to be secured thereto as at 15. The upper ends of the arms 13 are twisted at right angles as at 16 and are riveted or otherwise secured as at 17 to the said basket supporting ring 8.

60 In view of the above description it will be at once understood that I have provided a highly improved form of basket ball goal and one which embodies all of the characteristics of simplicity and rigidness of construction and inexpensiveness of manufacture.

65 Although I have herein shown and described the present embodiment of the present invention, it is nevertheless to be understood that minor changes may be made therein, without departing from the spirit and scope of the invention as claimed.

70 Having thus described my invention, what I claim as new and desire to secure by Letters Patent is:

75 A basket supporting device for a game apparatus including a hoop adapted to hold a basket and terminating in parallel abutting arms, and a pair of diverging legs extending substantially right angularly from the arms and adapted to be attached to the plane surface of a support.

80 In testimony whereof I affix my signature. 90

CLARENCE LANTRIP.
